CHARLES WITTE, OF BROOKLYN, NEW YORK.

Letters Patent No. 85,500, dated December 29, 1868.

IMPROVEMENT IN HAND-SHEARS.

The Schedule referred to in these Letters Patent and making part of the same.

To all whom it may concern:

Be it known that I, CHARLES WITTE, of the city of Brooklyn, in the county of Kings, and State of New York, having made certain new and useful Improvements in Hand-Shears; and I do hereby declare that the following is a full, clear, and exact description of the construction and operation of the same, reference being had to the accompanying drawings, making part of this specification, in which—

Figure 1 represents a perpendicular view of my improved hand-shears in the act of being used.

Figure 2 is a rear elevation of the same.

Figure 3 is a detached vertical section of the handle, used with the thumb of the hand, the plane of section being indicated by the line $z z$ in fig. 2.

Figure 4 is a perspective view of the palm of a hand, and indicating the relative position of the carpus and metacarpus-bones with the palm of the hand.

Similar letters of reference indicate corresponding parts in the several figures.

The nature of my invention consists in constructing the edge or flare of the handle of the shears, which is used to receive the pressure or bearing of the thumb in closing the shears, of such a peculiar form that the said flare of the shears receives the downward pressure or bearing, not of the thumb alone, as with other shears, but of the base of the thumb and the palm of the hand combined, as the inner periphery or rim of the said flare impinges, not upon the metacarpal bone of the thumb, as in other shears, but immediately at the articulation of the metacarpal bone of the thumb and the carpal bone of the wrist, whereby the joint action of the palm and thumb closes the shears, and the whole muscular force of the hand is utilized by this greatly-improved purchase, thus saving the operator the excessive fatigue and lameness resulting from continued cutting of heavy fabrics with shears constructed with the ordinary flare.

To enable others skilled in the art to make and use my invention, I will proceed to describe its construction and operation.

All the parts of my shears, with the exception of the handle A, which is operated usually by the thumb in other shears, are made nearly in the ordinary way; and the part B, of the handle A, which surrounds the thumb, is made also in the usual way; but instead of bringing the edge or flare C around the lower part of the thumb, with a flare only sufficient to take the pressure of the thumb above the joint or articulation of the carpus and metacarpus-bones, the said flare or rim C is extended further beyond and downward, and past the said joint or articulation, and follows the line $a b$, shown in fig. 4, where the said edge or rim C encounters the muscles of the thumb, nearly at their origin, which position is centrally in the palm of the hand, or nearly so, so that the flare of the shears is covered by and takes the pressure of all the muscles of the thumb down to the *palma facia* of the hand, and the contractile action of the whole hand is the motion which operates the shears, and which yields the important advantages before-mentioned.

Thus, whereas in shears as now constructed, and well exemplified in the patent to R. Heinish, dated September 20, 1859, the flange C is bent short downward, in such a manner that it comes into the palm of the hand, not touching the lower part of the thumb at all, my improved flange C is straight, thus bearing directly against the and near the fularum of the metacarpus-bone, following the line $a b$, shown in fig. 4.

I do not claim broadly a flange or flare at the part C, so that it may, in general, come in contact with the action of the metacarpus-bone; but

What I claim as new, and desire to secure by Letters Patent, is—

The flange C, when formed as shown, for the purposes herein set forth.

CH. WITTE.
